DESIGN FOR A BABY'S CRIB

Edward S. Swazey, Rochester, N. Y., assignor to Trimble Nurseryland Furniture, Inc., Rochester, N. Y., a corporation of New York

Application November 21, 1935, Serial No. 59,692

Term of patent 14 years

To all whom it may concern:

Be it known that I, Edward S. Swazey, a citizen of the United States of America, residing at Rochester, in the county of Monroe and State of New York, have invented a new, original, and ornamental Design for a Baby's Crib, of which the following is a specification, reference being had to the accompanying drawing, forming a part thereof.

The drawing is a perspective view of a crib embodying my new design, the appearance of the crib being substantially the same from either end.

I claim:

The ornamental design for a baby's crib, as shown and described.

EDWARD S. SWAZEY.
